CLAIM

The ornamental design for a door handle, as shown and described.

DESCRIPTION

FIG. 1 is a perspective top view of a door handle, according to one preferred embodiment of this invention;

FIG. 2 is a bottom perspective view of the door handle, as shown in FIG. 1;

FIG. 3 is a side view of the door handle, as shown in FIGS. 1 and 2;

FIG. 4 is a top view of the door handle, as shown in FIGS. 1 and 2;

FIG. 5 is a side view, opposite the side view shown in FIG. 3, of the door handle, as shown in FIGS. 1 and 2;

FIG. 6 is a bottom view of the door handle, as shown in FIGS. 1 and 2;

FIG. 7 is a rear view of the door handle, as shown in FIGS. 1 and 2; and,

FIG. 8 is a front view of the door handle, as shown in FIGS. 1 and 2.
